DESIGN FOR A REFRESHMENT STAND

Henry Oges, Buffalo, N. Y.

Application June 9, 1936, Serial No. 63,177

Term of patent 14 years

To all whom it may concern:

Be it known that I, Henry Oges, a citizen of the United States, residing at Buffalo, in the county of Erie and State of New York, have invented a new, original, and ornamental Design for Refreshment Stands, of which the following is a specification, reference being had to the accompanying drawing forming a part thereof.

The dominant feature of my design resides in the portions shown in full lines in the accompanying drawing, wherein:

I claim:

The ornamental design for a refreshment stand, substantially as shown and described.

HENRY OGES.
